UNITED STATES PATENT OFFICE.

LUTHER B. STOWELL, OF FRIENDSHIP, WISCONSIN.

HALTER.

SPECIFICATION forming part of Letters Patent No. 251,074, dated December 20, 1881.

Application filed October 9, 1880. (No model.)

To all whom it may concern:

Be it known that I, LUTHER B. STOWELL, of Friendship village, in the county of Adams and State of Wisconsin, have invented certain new and useful Improvements in Halters; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to headstalls and halters for domestic animals; and the novelty consists in the peculiar construction, arrangement, and adaptation of parts, whereby cheapness of manufacture, ease of application, efficiency of service, and less liability to get out of order are obtained, as will be more fully hereinafter set forth.

It is well known that many accidents occur in consequence of a multiplicity of buckles, joints, &c., the holes not only weakening the straps, but rendering them liable to crack at those places. To avoid these, and also to lessen the expense, the object of this invention is to employ as few straps or pieces of straps as possible, and consequently I use a minimum of buckles and joints.

In the accompanying drawings, Figure 1 is a bottom plan view, partly in perspective, showing the nose-straps turned to illustrate more fully the attachments of the buckles. Figs. 2, 3, and 4 are details, showing more fully the construction of the buckles; and Fig. 5, a perspective elevation, showing the device complete.

Referring to the drawings, A represents the cheek and crown straps, both in one piece of leather, and being secured in one of the buckles a, passes upward and through one of the buckles c, over, down upon the opposite side, through

the other cheek-buckle c, and terminates, after passing through and being secured, in the other buckle a. Within a loop in the cheek-buckles c is secured, by one or more snap-hooks, x, a throat-latch, C, formed of one piece of leather, secured at each end to the cheek-buckles c, the center of the body passing through a loop, D, formed of one piece of leather, both ends of which are secured in the buckle b, as plainly shown in Fig. 5.

B represents the hitching-strap, one end of which is passed through a fly-buckle, b', thence through the throat-buckle b, buckles a a, back through buckles b and b', and there secured, as shown. A portion of this strap is loosened; after passing through the buckle b, to form the nose-strap B', thus forming the nose-strap and hitching-strap of a single piece of leather, and with the necessity of but two holes for buckletongues in said strap. In this peculiar construction lies the gist of my invention.

It will thus be observed that in my complete halter I employ but four pieces of leather and a minimum number of buckles, and the device is consequently safer, better, and more convenient.

What I claim as new is—
The halter herein described, consisting of the hitching-strap and nose-band formed of a single piece doubled upon itself, the head-strap, throat-strap, and loop, comprising a halter and hitching-strap formed of four pieces, the whole constructed and adapted to serve relatively to the buckles a b c, snaps x, and fly-buckle b', as and for the purpose set forth.

In testimony that I claim the foregoing I have hereunto set my hand and seal this 16th day of August, 1880.

LUTHER B. STOWELL. [L. S.]

Witnesses:

G. W. WATERMAN,
J. B. HARRISON.
